UNITED STATES PATENT OFFICE.

JOSEPH SCHMIDT, JR., OF CHICAGO, ILLINOIS.

OAR.

1,066,662.

Specification of Letters Patent.

Patented July 8, 1913.

Application filed May 22, 1911. Serial No. 628,613.

To all whom it may concern:

Be it known that I, JOSEPH SCHMIDT, Jr., a citizen of the United States, residing at Chicago, in the county of Cook and State 5 of Illinois, have invented certain new and useful Improvements in Oars, of which the following is a specification.

This invention relates to an improvement in boat propelling oars; and has for its principal object to provide an oar having folding-blades capable of opening out and closing up automatically in accordance with the direction in which the oar is being moved in the water.

15 A further object is to provide a device of this character that can be used without raising the same out of the water for the return stroke.

Figure 1 is a rear elevation of an oar embodying the improved features. Fig. 2 is a front view in perspective. Fig. 3 is a plan. Fig. 4 is an end elevation.

A may represent the shaft, and B the oar blade.

25 In this instance the blade is made in two parts comprising the blade members or wings 5 and 6, which have a movement and action similar to a pair of wings. The shaft is provided with a thickened body-part 7 30 formed on the outer end thereof and which slopes away on each side to a rear sharp edge 8, as best shown in Fig. 4.

The forward or inner edge of the body 7 is beveled on each side to provide shoulders 35 9 and 10. The adjacent edges of the blade wings are beveled as at a, to correspond to and come to a close bearing on the shoulders 9 and 10 in strengthening the connection of the wings and limiting the opening 40 out movement thereof as they come to a stop on opposite sides. The companion wings are secured together in their operative relation by a number of hinges 11 and clip-plates 12 rigidly secured to the body-part 7.

The clip-plates 12 are provided with terminal ends 13 extending outward at right angles, the extreme ends of which are in-turned and provide a stop-rest to limit the closing movement of the collapsible blade wings, as indicated by dotted lines, Fig. 4. 45 The extreme closed position of the wings provides a separating space 14 so that the pressure of the water can act to return the same to their open working position for each power stroke. By this arrangement 50 the oars need not be raised out of the water for the return stroke and will have a feathering action. The rear edge 8 of the body-part being drawn to a sharp edge and the surface line of the thicker portion being 55 on a line with or a little outside of the folded position of the blade wings, offers the least possible resistance on the back movement.

In practical working, the blade-wings 60 open and close automatically with each stroke, the water acting as a cushion so that the change of position is gradual without jar or resulting injury to the oar-parts.

Having thus described my invention, what 65 I claim is:—

The combination with an oar-shaft provided with a thickened body-part formed on the outer end thereof, of companion wing-blades having an operative hinged 75 connection therewith, and the clip-plates secured to said body-part and having ends extending outward at right angles, the extreme ends of which are in-turned and form a stop-rest for the closing movement of said 80 blades.

In testimony whereof I affix my signature in presence of two witnesses.

JOSEPH SCHMIDT, Jr.
